UNITED STATES PATENT OFFICE.

FRED MERCHANT CARROLL, OF NEW HAVEN, CONNECTICUT, ASSIGNOR, BY MESNE ASSIGNMENTS, TO CHARLES L. STURTEVANT, TRUSTEE, OF WASHINGTON, DISTRICT OF COLUMBIA.

COMPUTING-MACHINE.

1,098,095.

Specification of Letters Patent. Patented May 26, 1914.

Application filed July 15, 1910. Serial No. 572,072.

To all whom it may concern:

Be it known that I, FRED M. CARROLL, a citizen of the United States, residing at New Haven, county of New Haven, State of Connecticut, have invented certain new and useful Improvements in Computing-Machines, of which the following is a full, clear, and exact description.

My invention relates to improvements in computing machines, and has for its object to produce a machine which when items of different classes, set up manually in one part, are printed, will automatically set up and print in another part other items corresponding to the respective classes of the original items.

The items set up on the manually actuated part of the machine I term "original" items, and the items set up on the other part 20 of the machine I term "secondary" items.

It further has for its object to produce a machine in which the original items will be added together and the secondary items will be added together.

25 It further has for its object to produce a machine that will print both the original items and the secondary items thus added, the original items in one column and the corresponding secondary items in another column.

It further has for its object to produce a machine which will print the total of the original items and the total of the secondary items.

35 The machine is particularly useful in making records of the amounts and fees of money orders and similar double records, and one of the embodiments hereinafter described will automatically record the fee of any 40 domestic money order whenever the amount of that money order is recorded and also add together the amounts of the several money orders recorded and the several fees for such money orders. It will also print the 45 amounts and corresponding fees separately, and when desired, will print the separate totals of the recorded money orders and the corresponding fees. Thus, when any amount 50 between 1 and 2.50 inclusive is recorded on the operating part of the machine, 3 will be registered in the fee recording part of the machine. When any amount

between 2.51 and 5.00 is recorded on the operating part, 5 will be registered by the fee recording part of the machine. When 55 any amount between 5.01 and 10.00 is recorded on the operating part, 8 will be registered by the fee recording part of the machine. When any amount between 10.01 and 20.00 is recorded on the operating part, 10 will be registered by the fee recording part of the machine. When any amount between 20.01 and 30.00 is recorded on the operating part, 12 will also be recorded. For 60 amounts from 30.01 to 40.00, 15 will also be recorded. For 40.01 to 50.00, 18 will also be recorded. For 50.01 to 60.00, 20 will also be recorded. For 60.01 to 75.00, 25 will also be recorded, and from 75.01 to 100.00, 30 will also be recorded. 70

The several groups of original items above specified constitute a plurality of classes, and each class contains a plurality of items, there being a separate secondary item for each class or group. 75

The invention may also be embodied with suitable changes in machines for recording any desired fee for any of several classes made up of other numbers than the numbers above specified. Where the classes begin 80 with the even hundreds and end with 99, 9.99 or 99.99, the embodiment of the invention is much more simple than where the classes conform to the requirements of the present money order systems. 85

For the sake of affording a clear understanding of my invention, I have chosen to describe and illustrate it in connection with mechanism of the well known Burroughs adding machine (see Burroughs' Patents 90 Nos. 504,963, 505,078, of September 12, 1893; McCauley Patent No. 823,474 of June 12, 1906;) to which my invention may be applied without material alteration of many of the old parts thereof, but it will be understood that my improvement is not limited in its application to this particular type of machine but that it may be embodied in connection with other machines. 95

The following is a description of an embodiment of my invention, reference being had to the accompanying drawings, in which—

Figure 1 shows a side elevation, certain

parts being broken away, of a commercial Burroughs machine known in the trade as "Style No. 3", modified so as to embody my invention. Fig. 2 shows an elevation of the other side with the frame removed. Fig. 3 shows a section of the keyboard of the same on the lines $x-x$ Fig. 9. Figs. 4 and 5 show in detail two actuating keys and circuit controlling devices controlled thereby. Fig. 6 shows a detail of the universal switch mechanism of Fig. 3, the same being a section on the line $y-y$ Fig. 3. Fig. 7 shows another sectional detail of universal switch mechanism of Fig. 3 on the line $z-z$ of said figure. Fig. 8 is a plan view of the resetting bars. Fig. 9 is a diagram of circuits for fees and original items grouped as in the present United States postal money order schedule. Fig. 10 is a modified diagram of circuits for a different grouping of original items and corresponding secondary items.

Referring more particularly to the drawings, I make use of keys or stops in seven of the nine rows of the Burroughs keyboard. (See Figs. 9 and 10.) In the right-hand row I utilize the keys "2," "3," "5" and "8;" in the next row I utilize the keys "1," "2" and "3." In the left-hand row I utilize the key 1 and in each of the four rows immediately to the right thereof I utilize the full series "1" to "9" inclusive.

Each key or stop 221 (Figs. 1, 2 and 3) actuates a lever 217, which moves the slide 214 of its series backward so as to actuate a detent 415 sufficiently to release the rack 610 of its series. The levers 217, with the exception of those which belong to the stops corresponding to the digit 9, have connected to them catches 270, which determine how far the rack bars 610 shall fall. These rack bars are each carried by one of a series of levers 611 pivoted on the shaft 600 and carrying at its rear end type members 618, which are forced against a suitable platen 599 by hammers 715.

There is one slide 214 and one rack 610 for each series of keys 221 in the machine, and an accumulating wheel 916 for each rack, so arranged that they accumulate the items set up, carrying from one to the next adjacent. The accumulating wheels when the racks fall are out of engagement therewith by reason of the movement of the trip 55 821, which actuates the oscillating member 913, so as to move the throwing member 914 as the shaft 800 (Fig. 2) turns counterclockwise. When the shaft 800 returns, thereby moving in the other direction, the 60 rocking member 913 is moved in the opposite direction and the accumulative wheels 916 are brought into engagement with the racks 610. At this time the racks are in depressed position, and as they are being returned to their original position by the yoke

613, the accumulating wheels 916 are revolved a distance corresponding to the values of the keys which were pressed to release the racks.

The slides 214 are held in their rearward position by detents 228, which are engaged by a universal bar 202 having an arm extending below its pivot carrying the pin 262. This pin 262 is engaged by the upper face of a cam 623 (Fig. 1) upon its upward movement. This cam 623 is pivoted to a lever, which in turn is pivoted at 600 and actuated by a portion of the rack member 311 bearing against the tail piece 622. In operation, the rack 311 is turned counterclockwise by a suitable handle connected to the shaft 300, and in this movement, the tail piece 622 follows it, so that the cam member 623 drops down below the pin 262. When the rack 311 returns to its normal position, it forces the cam member 623 upward so that its cam surface engages the pin 262 moving it toward the rear of the machine and thereby moving the universal bar 202 toward the front of the machine, causing it to act upon the levers 228 so as to release the slides 214 at the end of every cycle of the machine, whereupon the slides and stops 221 return to normal position.

Pivoted to the rack member 311 is a connecting bar 366 connected to the upper end of an arm 110 pivoted upon the shaft 100. This arm 110 carries a cross-rod 101, to which is connected a forked member 119 bearing a spring 880, which is connected to a pin 851 carried by a lever 811 pivoted at 800, the pin 851 sliding in the fork of the member 119. In this way a movement of the shaft 300 is conveyed to the shaft 800, the spring 880 acting to permit movement of the shaft 300 without moving the shaft 800 in case the parts become blocked for any reason, thereby preventing shock. The spring 180 connected to the shaft 101 and to the base of the machine returns the shaft 100 and also the shaft 300 to their normal positions. The items are not only accumulated upon the wheels 916 but are printed upon a paper carried by the platen 599 on account of the type members 618 being struck by the hammers 715 after they have been placed in proper position.

In order to print the totals, the total key 265 (Fig. 1) is depressed, moving the lever 227 and the bar 226 with its rod 226^a so as to release all the catches 415. Thereupon as soon as the cycle begins and the yoke 613 drops, the shifter 914, which has been moved downward because of the movement of the bar 911 connecting it with the lever 227 does not draw the wheels 916 out of engagement with the racks 610, but leaves them in engagement therewith, with the result that the downward movement of the racks 610 is determined by the movement of the 130

wheels 916 necessary to restore those wheels to zero position. The type members 618 are therefore positioned so as to print the members which were set up on their respective wheels 916. The wheels 916 are then disengaged from the racks 610 and those racks are restored to position, so that the machine is ready for another operation, the wheels 916 being left in zero position.

5 In order to make use of this machine in connection with my invention, I place plungers 1000 (Fig. 1) over the stops "2," "3," "5," and "8" in the right hand series and over stops "1," "2" and "3" of the 10 series adjacent thereto. These plungers are mounted in a suitable frame and are surrounded by springs 1001 which normally tend to depress the plungers. When any one of the plungers 1000 is depressed, the 15 stop 221 corresponding to it is depressed by it. These plungers 1000 are suitably mounted in bearings which permit them to slide vertically and have at their upper ends heads 1002 having lateral projections. Ad- 20 jacent to each of these plungers I mount a lever 1003, the upper end of which is normally held by a spring 1004 beneath the projection of the head 1002. On the outer 25 ends of these levers rest the cores 1005 of solenoids 1006. The levers corresponding to the stops "3," "5," and "8" have extended heads 1007, so that cores of two or more actuating solenoids may act upon said levers. In the case of the "5" stop, there 30 are three such cores with their corresponding solenoids, one of the solenoids 1006 being located above the others and its core being correspondingly extended. The 35 downward extensions from the solenoid 40 cores are reduced in diameter and are of non-magnetic material, preferably brass. In the second row of stops, the stops "2" and "3" have plungers located above them, controlled by similar levers, which levers 45 are controlled by electro-magnets similar to those of the stops "3" and "2" respectively of the other row. (See Figs. 9 and 10.) The "1" stop in the second row, however, is controlled by the four solenoids, 50 11', 12', 13', 14', Fig. 9. For the sake of compactness, these four solenoids are wound about two cores, each of which cores bears upon the extended head of the controlling lever. When the levers 1003 are beneath 55 the projections 1002, the stops are "cocked," as I term it, and when any solenoid is energized, its core moves its lever 1003 so that its plunger 1000 is no longer cocked, but is free to move under the influence of its 60 spring 1001 so as to depress its stop 221. In order to re-cock the plungers 1000, I provide two bars 1008 (Figs. 1, 8, 9 and 10) mounted on ends of levers 1008', whose other ends are connected by a bar 1010 so 65 that the bars 1008 are always maintained parallel to a given line. These bars 1008 have pins 1009 which project beneath the lateral projections of the heads 1002 of the plungers 1000. The bars 1008 are normally depressed. When, however, they are 70 raised, they elevate all plungers which have been released or uncocked and restore them to normal position, at which time the levers 1003 can come beneath the projections 1002 so as to hold the plungers cocked.

In order to elevate the bars 1008, I mount upon the shaft 501 (Fig. 1) a bent lever 1011, to which is connected a rod 1012 which rod is connected to the bars 1008. When the cross-rod 101 is moved toward the rear 75 by the turning of the arm 110, the latter part of which motion which takes place well along in the cycle of the machine, it moves the lever 1011 so as to elevate the rod 1012, which in turn elevates the bars 1008. 80 The cross-rod 101 then moves toward the front, releasing the lever 1011 and permitting it to resume its normal position.

85 The solenoids controlling the stops in the two right-hand series are in circuits controlled by switches actuated by stops in the left-hand series A', B', C', D', E' (Figs. 9 and 10) as hereafter explained, which are dominated by a normally open master switch F. (Figs. 1, 9 and 10.) The stop-controlled switches complete selected circuits through one or more of the solenoids 1006 except for the break at the master switch F. This break is momentarily closed at the beginning of each cycle so that when the machine starts a cycle to record an original item, the circuits through one or more of the solenoids 1006 are at once fully completed and the corresponding plunger or plungers 1000 released. The master switch F and 90 means for operating the same is shown in Fig. 1 and consists of two cups 1050 connected respectively to two circuit terminals and an inverted U-shaped member 1051 carried by a rod 1052. This rod is connected 95 to a bell crank lever 1053 movably mounted on the shaft 501 and normally held in raised position by a spring 1054. To the lower end of the bell crank lever a pawl 1055 is pivoted, which engages a projection 1056 on 100 the forked member 119 of the machine. In the path of this pawl is a pin 1057 secured to a stationary portion of the frame of the machine so as to be engaged by an incline on the pawl and release the pawl from the projection 1056 after the projection has moved a short distance to the right. This movement is sufficient to bring the U-shaped member 1051 into engagement with the mercury in the cups 1050. As soon as the pawl 1055 110 is disengaged from the projection 1056, the contact between the member 1051 and the mercury in the cups 1050 is broken so that the solenoids 1006 in circuit are only 115 momentarily energized. This, however, is all 120

125 130

that is necessary to pull the triggers 1003 so as to uncock the plungers 1000, and leaves the triggers and plungers free to be re-cocked at the end of the cycle after the 5 original and secondary items have been recorded.

The series of stops A', B', C', D' and E' are the stops on which the original items are set up. The stops of the third and 10 fourth series of the complete Burroughs keyboard are not shown in Figs. 9 and 10, since, in the embodiment being described, they perform no function. Stop "1" in the left-hand series E' is the only stop of that series 15 shown since the other stops of that series also perform no function.

For each series of stops A', B', C', D' and E', I provide universal switch mechanism, such switch mechanism being shown in Fig. 20 9 at A, B, C, D and E. The universal switch mechanism C is shown in detail in Figs. 3, 6 and 7. The universal switch mechanisms are all similar, with the exception of the various circuit making devices 25 which they actuate. They each consist of a bar 1013 carried by the ends of levers 1014, whose corresponding arms are of the same length and whose free ends are connected by a bar 1015 so that the bar 1013 as it moves 30 is always parallel with a given line. To the bar 1013 a rod 1016 is connected by the same rivet that connects the lever 1014, the lower end being connected to a bell crank lever 1017 pivoted at 1018 to one side of a vertical 35 plate 210. On the other side of the plate 210 the detent 228 is pivoted for retaining the slide 214 when the same has been moved into its rearward position by the depression of any one of the actuating stops 221. On 40 this slide 214 I provide a projection 1019 which engages the lower end of the lever 1017, and, when the slide 214 is moved into its rearward position, actuates that lever so as to cause the bar 1016 to raise the bar 45 1013 and hold it in raised position as long as the slide 214 is retained in its rear position. The hundreds bar 1013 (series C) is provided with two circuit making devices 1020, each such as shown in detail in Fig. 7. These 50 two circuit making devices together with the corresponding stationary contacts, are represented in Fig. 9 by the third and fourth switches of the universal switch mechanism C and consist of two mercury cups 1022 electrically connected together, into which dip the ends of two curved circuit terminals 1023 carried by insulating supports 1024. Whenever the bar 1013 is in depressed position, the terminals 1023 are electrically disconnected and whenever the bar 1013 is in raised 55 position the terminals 1023 are electrically connected. They are, therefore, normally disconnected.

The hundreds bar 1013 (series C) also 60 carries two circuit controlling devices 1025,

which, together with the co-operating stationary contacts, are represented in Fig. 9 by the first and second switches of the universal switch mechanism C. Fig. 6 shows a detail of one of these controlling devices, 70 the same consisting of an inverted U-shaped member 1026, whose lower ends dip into mercury cups 1027 carried by suitable insulating supports 1024. When the bar 1013 is depressed, the mercury cups 1027 are electrically connected by the member 1026 and when the bar 1013 is raised, the mercury cups are electrically disconnected, the result being that the circuit through this switching device is normally closed. 75

Surrounding the stops of the series A', B', C', D' and E' is an insulating support 1028, (Figs. 2 and 3) for mercury cups 1029 and pins 1030 (Figs. 4 and 5), with which U-shaped members 1031 and cups 1032 respectively engage and disengage under differing conditions. The "1," "2," "3," "4" 80 keys of series C' Fig. 3, are each provided with one U-shaped member 1031, which co-acts with corresponding cups 1029. The "6," "7," "8" and "9" keys are each provided with one such member 1031, adapted to engage with cups 1029 and also with one pair of cups 1032 normally engaging contacts 1030. The key "5" is provided with 85 three such inverted U-shaped members 1031, which co-act with three separate pairs of mercury cups 1029 and is also provided with one pair of electrically connected mercury cups 1032 into which dip terminals 1030 90 carried by the support 1028, as shown in Fig. 5. The mercury cups 1032 although connected with one another are insulated from the key. The U-shaped members 1031 are also insulated. 95

The circuit controlling devices on the universal switch A (Fig. 9) are different in number and arrangement from those of switch C, Fig. 3, above described. Counting from the bottom, the first, third, 100 fourth and seventh controlling devices are like those shown in Fig. 6. Counting from the bottom, the second, fifth, sixth, eighth and ninth circuit controlling devices are similar to that of Fig. 7. 105

In the universal switch B (Fig. 9) corresponding to the series of keys B', the construction and mode of operation is the same as that shown in Fig. 3, with the exception of the number and arrangement of the controlling devices. In this universal switch B', counting from the bottom, the first, second, and fifth circuit controllers are of the normally closed circuited type, shown in Fig. 6. The third, fourth, sixth and 110 seventh are of the normally open circuited type shown in Fig. 7. 120

In the universal switch mechanism C (Fig. 9) as above described, the first and second switches are of the normally closed 125

type shown in Fig. 6 and the third and fourth are of the normally open type shown in Fig. 7.

In the universal switch D (Fig. 9) corresponding to the series D', when counting from the bottom, the first and third switches are of the normally closed type shown in Fig. 6, and the second and fourth switches are of the normally open type shown in Fig. 7. The switch of the universal mechanism E is of the normally closed type of Fig. 6.

Referring to the manually actuated keys, the keys of series A', which correspond to the unit keys, have no switches except the universal switch mechanism A, which is actuated by its slide 214 when any of the unit keys are depressed. The keys of the series B', (Fig. 9) the tens keys, are some of them provided with switches and some 20 of them without switches, thus the tens keys "1," "2," "3," "4" have no switches, but each of them actuates the universal switch mechanism B. The tens keys "5," "6," "7," "8" and "9" have each one switch 25 of the normally open type of Fig. 4 and one switch of the normally closed type of Fig. 5, and also actuate the universal mechanism B. The switches of the hundreds keys have already been described in detail. The 30 switches of the thousands keys (Fig. 9) are the most complicated. Each of the thousands keys "1," "2," "3," "4," "5," and "6" have two switches of the normally open type, Fig. 4. Key 7 has five switches. 35 Counting from the bottom its first, second, third and fifth switches are of the normally open type of Fig. 4, and its fourth switch is of the normally closed type of Fig. 5. The thousands keys "8" and "9" have each 40 one switch of the normally open type of Fig. 4. The ten-thousands key "1," series E', (Fig. 9) has one switch of the normally open type of Fig. 4.

As a matter of symbols in showing the 45 switches of the two types, the symbol shown in the key of series E' indicates in all instances (whether in connection with the universal switch mechanism [Fig. 7] or in connection with the key switches [Fig. 4]) a 50 switch of the normally open circuit type. The symbol is not intended to represent the construction, but is simply a symbol. The symbol for the normally closed circuit switch, such as shown in either Fig. 5 or 55 in Fig. 6, is illustrated in the lowest switch of key "5" in the tens series B' and this symbol is used to indicate such a switch in both the key switches and the universal switches and is not intended to represent the 60 construction of the switches. The symbols are shown below the structures in Figs. 4, 5, 6 and 7.

Having described the apparatus and its 65 mechanical operation, I will now describe the electrical connections and the circuits

formed by actuating any of said keys for setting up original items corresponding to the money order schedule and in so doing refer to Fig. 9. In this Fig. 9, G is any convenient source of current. A, B, C, D, 70 E as above stated, are series of universal switches, that is, switches which are actuated whenever any key of the corresponding denomination, units, tens, hundreds, thousands, ten thousands is actuated. A', B', C', 75 D', E' are series of keys for the respective denominations, units, tens, hundreds, thousands, ten-thousands. Whenever a unit or a tens key is actuated and the thousands and ten thousands keys are not actuated, a circuit is completed through the conductor 50 and the actuated units, tens or hundreds switch connected thereto to the third switch (normally closed) of series D and thence through the lower switch (normally closed) 80 of series C to conductor 3, which is connected to the solenoid 31 of the right-hand registering key "3" and through that solenoid to the return wire R, and this is the only path which is thus completed. When 85 key "1" of the hundreds series is actuated, the circuit is the same to the switch of that key. From thence it passes through the switch of hundreds key "1" to the conductor 3, the path through the lower switch 90 (normally closed) of series C being at that time interrupted. When the hundreds key "2" is operated and any key of a value lower than the tens key "5," the circuit to the hundreds key "2" is the same but at 95 100 that point passes through the normally open but now closed switch of the hundreds key "2"; from thence it passes through the lower normally closed switch of the tens key "5" and the normally closed switches 105 of the tens keys "6," "7," "8," "9" to the conductor 3², and thence to the second solenoid 32 of the right-hand registering key "3" and to the return conductor R. When the hundreds key "2," the tens key "5" and 110 no units key are actuated, the circuit is the same to the hundreds key "2," thence it passes through the normally open but now closed switch of the hundreds key "2" to the upper (normally open) switch of the 115 tens key "5" to the first, i. e., lowest, switch of the universal mechanism A and thence to conductor 3² and the solenoid 32 of the right-hand registering key "3" to the return R. From this it will be seen that 120 whenever any numeral between 1 and 250 inclusive is set up, the plunger of the right-hand registering key "3" is released and that plunger only.

When the hundreds key "2" and the tens 125 key "5" and one of the units keys are actuated, the circuit is the same with the exception that instead of passing through the lower switch of the universal mechanism A, it passes through the second, i. e., next to 130

lowest switch of the universal series A and thence to the central solenoid 52 of the three solenoids controlling the registering key "5" and to the return R. When the hundreds key "2" and any one of the tens keys "6," "7," "8," "9," together with or without a unit key, are actuated, the circuit to the hundreds key "2" is the same. It then passes through the switch of key "2," the right-hand switch of whichever of the tens keys "6," "7," "8," "9," was actuated, to the middle actuating solenoid 52 of the registering key "5" and to the return conductor R. Whenever either of the hundreds keys "3" or "4" is actuated, either together with or without a tens or units key, the circuit to the hundreds key "2" is the same. It cannot pass through the lowest (normally closed) switch of the universal switch C because that is now open. It therefore passes through the switch of the hundreds key "3" or hundreds key "4," according to which has been actuated to the middle solenoid 52 of the registering key "5" and thence to the return conductor R. When the hundreds key "5" alone is actuated, the circuit to the hundreds key "2" is the same but instead of passing through the switches of the hundreds keys "2," "3" or "4," it passes through the second switch of the hundreds key "5" and thence to the fifth switch of the universal series B and the seventh switch of the universal series A, these switches being normally closed, to the middle solenoid 52 of the registering key "5" and thence to the return. From this it will be seen that any number between 251 and 500 inclusive when set up, will result in actuating the registering key "5" and no other key. When the hundreds key "5" and any tens or units key is actuated, the circuit to the hundreds key "5" is the same as just outlined, passing through the second switch of the hundreds key "5," from thence, however, it passes through either the fourth switch of the universal series B or the sixth switch of the universal series A, or both, according to whether a tens key or units key or both was actuated, to the lower solenoid 81 of the registering key "8" and thence to the return.

When either hundreds key "6," "7," "8" or "9" is actuated, either together with or without a tens or units key, the circuit is the same past the hundreds keys "2," "3," "4," thence it passes through the conductor 42, thence it passes through the first switch of the thousands universal switch (normally closed) to the conductor 43. From thence it passes through one of the switches of the hundreds keys "6," "7," "8," "9," according to the one which has been actuated, through the conductor 44. It then passes through the fourth switch of the thousands key "7" (normally closed) to the lower

solenoid 81 of the registering key "8" and thence to the return R.

When only the thousands key "1" is actuated, the circuit instead of passing through the conductor 50 as heretofore, passes through the conductor 60, the universal switches in the series A, B and C controlling that circuit being closed because normally closed and the second universal switch of the series D being closed because actuated. The current flows through those switches to the lower switch of the thousands key "1," from thence it passes through the conductor 8 to the lower solenoid 81 of the registering key "8" and thence to the return R. From this it will be seen that when any number is set up between 501 and 1000 inclusive, the registering key "8" will be actuated and no other key and the amount "8" recorded.

When the thousands key "1" is actuated, together with any keys of the units, tens or hundreds series, the circuit instead of passing through the conductor 60 passes through the conductor 70, and through such of the units, tens or hundreds universal switches in that circuit which may have been closed, to and through the upper switch of the universal series D, thence it passes to the upper switch of the thousands key "1," from thence it passes to the conductor 10, through one of the windings, 11' of the double wound right-hand solenoid of the registering key "1" to the return R. When the thousands key "2" alone is actuated, the circuit passes through the conductor 60 to the lower switch of the thousands key "2," through which it passes to the conductor 10 and to the same winding 11' of the right-hand solenoid of the registering key "1" to the return R. From this it will be seen that whenever any number between 1001 and 2000 is set up, the registering key "1" will be actuated and that key alone. This key being in the tens position will register the amount "10".

When the thousands key "2" and keys of lower denominations are actuated, the current passes through the conductor 70 and the switches controlling the same, as above described, to the upper switch of the thousands key "2," from thence it passes to the conductor 12, to which one winding 12' of the left-hand double-wound solenoid controlling the registering key "1" and the solenoid 21 controlling the right-hand registering key "2," are connected in parallel. The circuit therefore leads through these two windings in parallel to the return R. When the thousands registering key "3" alone is actuated, the current goes through the conductor 60 and the switches controlling the same to the lower switch of the thousands key 3, from thence it passes to the conductor 12 and to the return conductor through the windings 12' and 21 of the keys "1" and right-hand

key "2" just referred to. From this it will be seen that whenever any number between 2001 and 3000 inclusive is set up, the key "1" and the right-hand key "2" will be actuated so as to register "12".

When the thousands key 3 is actuated, together with any keys of lower denominations, the circuit passes through the conductor 70 and the universal switches controlling the same to the upper switch of the thousands key "3", from thence it passes to the conductor 15 to which the other winding 13' of the double-wound right-hand solenoid of registering key "1" and the winding of the lower solenoid 51 of registering key "5", are connected in parallel and to the return R. The circuit, therefore, passes through these two magnets to the return, so that the amount "15" is set up. When the thousands key "4" alone is actuated, the circuit passes through the conductor 60 to the lower switch of the key "4" and thence to the conductor 15 and through the windings 13' and 51 connected in multiple thereto, so as to set up the amount "15". From this it will be seen that whenever any number between 3001 and 4000 inclusive is set up, the amount "15" will be set up on the registering keys.

When the thousands key "4" and any keys of lower denominations are actuated, the circuit passes through the conductor 70 to the upper switch of the thousands key "4" and thence to the conductor 18, to which the other winding 14' of the left-hand double-wound solenoid of recording key "1" and the upper solenoid 82 of recording key "8" are connected in multiple and to the return conductor R. When the thousands key "5" alone is actuated, the current passes through the conductor 60 to the lower switch of the thousands key "5" and to the conductor 18 to which windings 14' and 82 of the recording keys "1" and "8" are connected in multiple, as just described. When therefore any number between 4001 and 5000 inclusive is set up, the recording keys will be actuated to record the amount "18".

When the thousands key "5" and any keys of lower denominations are actuated, the current passes through the conductor 70 and the universal switches controlling the same to the upper switch of the thousands key "5", from thence it passes to the conductor 20, from which it passes to the upper solenoid 212 of the left-hand registering key "2" and to the return R. When the thousands key "6" alone is actuated, the current passes through the conductor 60 to the second switch of the thousands key "6", from which it passes to the conductor 20, which, as just stated, leads to the solenoid 212 of the left-hand key "2". When, therefore, any number between 5001 and 6000 inclusive is set up, the left-hand recording key "2"

will be released and the amount "20" will be set up.

When the thousands key "6", together with keys of lower denominations are actuated, the current passes through the conductor 70 and the universal switches controlling the same to the lower switch of the thousands key "6", from thence it passes to the conductor 25, to which the winding of the lower solenoid 210 of the left-hand recording key "2" and the winding of the upper solenoid 53 of the recording key "5" are connected in multiple and to the return. When any number between 6001 and 6999 is set up, the current will pass through the windings just referred to and the amount 25 will be recorded.

When the thousands key "7" alone is actuated, the current flows through the conductor 80 to the second switch of the thousands key "7", thence to the upper switches (normally closed) of hundreds keys 9, 8, 7 and the lowest switch of hundreds key 6 to the lowest switch of the hundreds key "5" (normally closed) and thence to the conductor 25, which, as just described, energizes windings of the recording keys to set up the amount "25". This circuit is the same whenever the thousands key "7" and any one of the units or tens keys or the hundreds keys "1", "2", "3", "4" are actuated. When the thousands key "7" and the hundreds key "5" alone are actuated, the circuit flows through the conductor 80 to and through the second switch of the thousands key "7", through the normally closed switches of hundreds keys "6", "7", "8" and "9", the third switch of the hundreds key "5", through the lower universal switch of series B and the third universal switch of series A to the conductor 25 and the windings 210 and 53 before referred to. From this it will be seen that whenever a number between 6001 and 7500 inclusive is set up the recording keys will register "25".

Whenever the thousands key "7", the hundreds key "5" and any key of lower denomination are actuated, the current passes through the conductor 70 to and through the third switch of the thousands key "7" to the conductor 43, thence it passes through the lower switch of the thousands key "7" to one or both of the uppermost universal switches of series A or B, thence back to the upper switch of hundreds key "5" to conductor 44, thence through the upper switch of thousands key "7" to the conductor 30, thence it passes the winding of the solenoid 301 of the left-hand recording key "3" and to the return R. When the thousands key "7" and any one of the hundreds keys "6", "7", "8", or "9", either with or without one of the units or tens keys, are actuated, the circuit passes through the conductor 70 to the third switch of the thousands key 125

"7" to the conductor 43, thence through one of the switches of the hundreds keys "6", "7", "8" or "9", to the conductor 44, thence through the upper switch of the 5 thousands key "7" to the conductor 30 and thence to the winding of the solenoid 301 of the left-hand recording key "3".

- When the ten-thousands key "1" is actuated, the circuit passes through the conductor 80 to the switch of the ten-thousands key "1" and thence to the conductor 30, from which it passes, as before described, through the winding of the solenoid 301 controlling the left-hand recording key "3" 10 to the return R. From the foregoing it will be seen that whenever any number between 7501 and 10,000 inclusive is set up, the recording keys will be actuated to register the amount "30." 15
- 20 In the modified arrangement of circuits shown in the diagram of Fig. 10, provision is made for setting up the original and secondary items as follows: Secondary 3 when original 1 to 299 inclusive are set up, secondary 5 when original 300 to 499 inclusive are set up, secondary 8 when original 500 to 999 inclusive are set up, secondary 10 when original 1000 to 1999 inclusive are set up, secondary 12 when original 2000 to 2999 inclusive are set up, secondary 15 when original 3000 to 3999 inclusive are set up, secondary 18 when original 4000 to 4999 inclusive are set up, secondary 20 when original 5000 to 5999 inclusive are set up, secondary 25 25 when original 6000 to 7999 inclusive are set up, secondary 30 when original 8000 to 10000 inclusive are set up.

Because the groups begin with even hundreds instead of ending with even hundreds, 40 as in the money order schedule, the number of circuits and switches is greatly reduced. In this diagram, *a* *b* *c* *d* *e* represent universal switch mechanisms, each actuated by any key of the corresponding series *a'* *b'* 45 *c'* *d'* *e'*. When no key is actuated to set up an original item, the circuit from the source G is open. If a tens or hundreds key is actuated, the normally open contacts of the universal switches *a* and *b* are closed, establishing a circuit through the conductors 50^a and the normally closed contacts of the universal switches *d* and *e* in series therewith through the lower (normally closed) contacts of the universal switch *e* to the 55 conductor 3^a, which leads to the solenoid 31^a of the right-hand secondary key 3 and to the return R. When the hundreds keys "1" or "2" are actuated, either with or without a tens or units key, the circuit before referred is interrupted at the lower (normally closed) contacts of the hundreds universal switch *c*, but the current after passing through the lower (normally closed) contacts of the universal switch *e* is free to

pass through one of the switches of the 65 hundreds keys "1" or "2" according to which was actuated, to the conductor 3^a, through which it passes through the magnet 31^a, to the return R. It will be seen from the foregoing that whenever any original 70 item between 1 and 299 inclusive, is set up, that the right-hand secondary key 3 will be actuated so as to set up the secondary item 3.

When either of the hundreds keys "3" 75 or "4" is actuated, the lower (normally closed) contacts of the universal switch *c* are thereby opened, so that the current must pass through the actuated switch 3 or 4, to the conductor 5^a, and thence through the 80 solenoid 52^a to the return R, actuating the secondary key 5, so that whenever any original item between 300 and 499 inclusive is set up the secondary key 5 will be actuated to set up the secondary item 5. In a similar 85 manner, when any of the hundreds keys 5, 6, 7, 8 or 9, either with or without tens and units keys, are actuated, the current after passing the lower normally closed contacts of the universal switches *d* and *e* passes 90 through the switch of the actuated key to the conductor 8^a, and thence to the solenoid 82^a controlling the secondary key 8, and to the return, so that when any original item between 500 and 999 is set up, the secondary 95 item 8 is set up.

When any thousands key is actuated, the universal switch *d* is actuated so as to interrupt the circuit through the conductor 50^a. When any of the thousands keys "1" 100 to "7" inclusive are actuated, a circuit is completed through the actuated switch and the conductor 60^a, the upper contacts of the universal switch *e* being normally closed. When the thousands key 1 is actuated, 105 either with or without a units, tens or hundreds key, the circuit passes from the conductor 60^a to the switch of thousands key "1" and conductor 10^a to the winding 111^a of the right-hand solenoid of the secondary 110 key "1," so that whenever any number between 1000 and 1999 is set up, the secondary item 10 will be recorded, the recording key "1" being in the tens position. When the thousands key 2 is actuated, either with or 115 without keys of lower denomination, a circuit is established through the conductor 60^a, the switch of thousands key "2," conductor 12^a, windings 112^a and 21^a, connected in parallel to the return R, so that whenever 120 any original item between 2000 and 2999 is set up, the secondary item 12 will be set up on the secondary keys.

When the thousands key "3" is actuated, a circuit is completed through the conductor 125 60^a, the switch of thousands key "3," conductor 15, solenoid windings 113^a and 51^a, connected in multiple to the return R, so

that whenever any original item between 3000 and 3999 is set up, the secondary item 15 will be set up.

Whenever the thousands key "4" is actuated, either with or without keys of lower denominations, the circuit through the conductor 60^a is completed through the switch of the thousands key "4" and the conductor 18^a, to the winding 114^a of the left-hand solenoid of the secondary key "1" and the winding 81^a of the secondary key 8 to the return, so that whenever any original item between 4000 and 4999 is set up, the secondary item 18 will also be set up.

15 Whenever the thousands key "5" is actuated, a circuit is completed through the conductor 60^a, the switch of the thousands key "5," the conductor 20^a, to the winding of the lower solenoid 201^a of the left-hand secondary key "2," to the return, so that whenever any original item between 5000 and 5999 is set up, the secondary item 20 will also be set up.

Whenever either of the thousands keys 25 "6" or "7" is actuated, a circuit is completed through the conductor 60^a and the switch of the key actuated, to the conductor 25^a, thence through the winding of the upper solenoid 212^a of the left-hand secondary key 30 "2" and the winding of the upper solenoid 53^a of the key "5," to the return, so that whenever any original item between 6000 and 7999 is set up, the secondary item 25 will also be set up.

35 Whenever either the thousands keys "8" or "9" is actuated, a circuit may be established through the conductor 80^a instead of 60^a as heretofore, although this is not necessary. In the diagram, whenever either of the thousands keys "8" or "9" is actuated, a circuit is established through the conductor 80^a and the switch of the particular key actuated, to the conductor 30^a, and thence passes through the solenoid winding 301^a of the left-hand secondary key "3." When the ten-thousands key "1" is actuated, a circuit is established through the conductor 80^a and the switch of the actuated key, to the conductor 30^a and thence through the solenoid 50 301^a aforesaid. From this it will be seen that whenever any original item between 8000 and 10000 inclusive, is set up, that the secondary item 30 will also be set up.

The operation of the machine is as follows: Original items are set up by manipulating the stops of series A' B' C' D' E' (Fig. 9) in the usual manner in which the Burroughs machine is ordinarily used. The setting up of an original item on these keys completes a circuit through one or more solenoids 1006 with the exception of the break at the switch F as heretofore described at length. The shaft 300 is then turned by the handle in the ordinary manner. This re-

sults in moving the member 119, which moves the bell crank 1053 until the pawl 1055 is released from the projection 1056 by the pin 1057. During this movement of the bell crank, the contact 1051 engages the mercury in the cups 1050, thus fully completing the circuit above referred to. The corresponding plungers 1000 are thereby released so as to actuate the corresponding recording stops at the very beginning of the cycle. The machine then prints and accumulates as in the ordinary operation, and when the totalizing key 265 is used, prints the totals. As soon as the plungers 1000 are released, the circuit at F is broken and remains broken until the next cycle. Toward the end of the first half of the cycle, the cross-bar 101 engages the lever 1011, lifting the rod 1012 and the parallel bars 1008. This lifts the released plungers 1000 until the levers 1003 pass beneath the projections 1002 so that the plungers are re-cocked and ready for further use. Upon the completion of the cycle, the machine is thus ready to have another original item set up and to record them, together with corresponding secondary items. One portion of the accumulating wheels 916 is used for the original items and others for the secondary items, there being no conflict until the fees amount to one hundred dollars, so that it is not necessary, under ordinary circumstances, to remove the carrying mechanism to prevent carrying from the fourth to the fifth accumulating wheel. The left-hand part of the machine used for original items is practically a mechanism independent of the right-hand part and vice versa, except for the electrical intercommunication and the single driving crank, certain other parts being used in common instead of being duplicated.

The invention permits of various modifications without departing from the spirit thereof as will be evident to those skilled in the art.

What I claim is—

1. In a computing machine, the combination of a group of main stops, a group of secondary stops, electro-magnetic means for controlling one of said secondary stops, circuit terminals, a source of current therefor, switches controlled by said main stops whereby when any stop of said main stops is actuated, the electro-magnetic means of said secondary stop will also be connected between said circuit terminals.

2. In a computing machine, the combination of a group of main stops and a group of secondary stops, the main stops being of different denominations, electro-magnetic means for controlling said secondary stops, circuit terminals, a source of current therefor, and switches actuated by said main stops whereby the electro-magnetic means

- controlling a given one of said secondary stops will be connected between said circuit terminals when a plurality of main stops of different denominations are actuated.
5. 3. In a computing machine, the combination of a group of main stops and a group of secondary stops, the main stops being of different denominations, electro-magnetic means for controlling said secondary stops, 10 circuit terminals, a source of current therefor, switches actuated by said main stops whereby the electro-magnetic means controlling a given one of said secondary stops will be connected between said circuit terminals when a plurality of main stops of different denominations are actuated, an additional group of main stops, and dominating electric switches controlled by said additional group of main stops whereby, whenever one of said additional group of main stops is actuated, the electro-magnetic means controlling a different secondary stop will be connected between said circuit terminals.
15. 4. In a computing machine, the combination of a group of secondary stops comprising stops of different denominations, a group of main stops, electro-magnetic means for actuating two secondary stops of different denominations, circuit terminals, a source of current therefor, and switches controlled by each stop of said group of main stops completing electric connection with said terminals whereby the electro-magnetic means of two secondary stops of different denominations will be connected between said terminals whenever any one stop of said main group is actuated.
20. 5. In a computing machine, the combination of secondary stops of different denominations, a group of main stops, electro-magnetic means controlling the same, circuit terminals, a source of current therefor, normally open switches and normally closed switches controlled by each stop of said main group of stops whereby, when said main stops are actuated, the electro-magnetic means controlling a given secondary stop will be selected and connected between said terminals.
25. 6. In a computing machine, the combination of a group of secondary stops, a group of main stops, electro-magnetic means controlling said secondary stops, circuit terminals separated so as to constitute a normally open circuit for said electro-magnetic means, a source of current therefor, selective switches controlled by said main stops for selecting a given electro-magnetic means and connecting it between said terminals when any of said main stops are actuated, and means for closing the circuit at said terminals temporarily during the cycle of the machine.
7. In a computing machine, the combination of a group of secondary stops, a group of main stops, circuit terminals, a source of current therefor, and a plurality of switches controlled by each stop of said main group, making and breaking electric connections whereby a given electro-magnetic means is electrically connected between said circuit terminals whenever one stop of the main group of stops is actuated. 65
8. In a computing machine, the combination of a group of secondary stops, a group of main stops, a plurality of electro-magnetic means controlling said secondary stops respectively, circuit terminals, a source of current therefor, selective switches comprising a plurality of switches controlled by each stop of said main group making and breaking electric connections, and individual switches actuated by the individual stops of said main group, whereby a given one of said electro-magnetic means is selected and electrically connected between said circuit terminals whenever one of the main group of stops is actuated. 70
9. In a computing machine, the combination of a group of secondary stops of different denominations, a group of main stops, circuit terminals, a source of current therefor, electro-magnetic means controlling a plurality of secondary stops of different denominations, selective switches comprising universal switches controlled by a plurality of said main stops and individual switches controlled by said main stops severally, whereby the electro-magnetic means controlling a plurality of secondary stops of different denominations are connected between the circuit terminals when any stop of said main group of stops is actuated. 90
10. In a computing machine, the combination of a group of secondary stops, a plurality of groups of main stops, main terminals, a source of current therefor, electro-magnetic means controlling one of said secondary stops, additional electro-magnetic means controlling another of said secondary stops, switches controlled by any stop of one main group for connecting one electro-magnetic means between said main terminals of the circuit, and switches controlled by any stop of the other main group of stops for breaking said connection and establishing an electric connection of the electro-magnetic means of the other secondary stop between said main terminals. 105
11. In a computing machine, the combination of a group of main stops, a group of secondary stops, electro-magnetic means for controlling one of said secondary stops, circuit terminals, a source of current therefor, switches controlled by said main stops whereby, when any stop of said main stops is actuated, the electro-magnetic means of 110
- 120
- 125

said secondary stop will also be connected between said circuit terminals, and means for temporarily connecting the source of current between said main terminals at the beginning of a cycle of the machine.

12. In a computing machine, the combination of a group of main stops and a group of secondary stops, the main stops being of different denominations, electro-magnetic means for controlling one of said secondary stops, circuit terminals, a source of current therefor, switches actuated by said main stops whereby the electro-magnetic means controlling a given one of said secondary stops will be connected between said circuit terminals when a plurality of main stops of different denominations are actuated, and means for temporarily connecting the source of current between said circuit terminals at the beginning of a cycle of the machine.

13. In a computing machine, the combination of a group of main stops and a group of secondary stops, the main stops being of different denominations, electro-magnetic means for controlling one of said secondary stops, circuit terminals, a source of current therefor, switches actuated by said main stops whereby the electro-magnetic means controlling a given one of said secondary stops will be connected between said circuit terminals when a plurality of main stops of different denominations are actuated, an additional group of main stops, dominating electric switches controlled by said additional group of main stops whereby whenever one of said additional group of main stops is actuated, the electro-magnetic means controlling a different secondary stop will be connected between said circuit terminals, and means for temporarily connecting the source of current between said main terminals at the beginning of a cycle of the machine.

14. In a computing machine, the combination of a group of main stops, a group of secondary stops, springs for moving said secondary stops, triggers restraining said secondary stops, electro-magnetic means for releasing said triggers, a source of current for said electro-magnetic means, circuit terminals, and means controlled by said main stops for connecting said electro-magnetic means between said terminals.

15. In a computing machine, the combination of a group of main stops, a group of secondary stops, springs for moving said secondary stops, triggers restraining said secondary stops, electro-magnetic means for releasing said triggers, a source of current for said electro-magnetic means, circuit ter-

minals, means controlled by said main stops for connecting said electro-magnetic means between said terminals, and cycle performing means for temporarily connecting said source of current between said terminals. 65

16. In a computing machine, the combination of a group of main stops, a group of secondary stops, springs for moving said secondary stops, triggers restraining said secondary stops, electro-magnetic means for releasing said triggers, a source of current for said electro-magnetic means, circuit terminals, and means controlled by said main stops for connecting said electro-magnetic means between said terminals, and cycle performing means for temporarily connecting said source of current between said terminals and for restoring said secondary stops to initial position after the source of current has been disconnected from between said terminals. 70 75

17. In a machine of the character described, the combination of a plurality of groups of manually operated main type controlling stops, an equal number of secondary type controlling stops each corresponding to one group of main stops and controlling connections between all stops of any group of main stops and a corresponding secondary stop. 85 90

18. In a machine of the character described, the combination of a type setting stop, a spring normally tending to actuate the same, a detent restraining said spring and electromagnetic means for releasing said detent. 95

19. In a machine of the character described, a plurality of branch electric circuits, a main circuit to which said branch circuits are connected in multiple, manual switches in the branch circuits and a main switch in the main circuit, cycle performing means for closing said main switch and means for locking said manual switches during the performance of a cycle. 100 105

20. The combination with an adding machine comprising sections for recording amounts in separate columns, said sections comprising printing members, and the usual stops and keys for controlling said members, of supplemental stops for one section, electro-magnets for operating said supplemental stops, circuits including the coils of said electro-magnets, and means operated by keys of another section for closing said circuits. 110 115

FRED MERCHANT CARROLL.
